CLAIM

The ornamental design for gallbladder forceps, as shown and described.

DESCRIPTION

FIG. 1 is a right side elevational view of a gallbladder forceps showing our new design, the tubular housing being continuous over the area indicated by dot-dash lines;

FIG. 2 is a top plan view thereof;

FIG. 3 is a rear elevational view thereof;

FIG. 4 is a left side elevational view thereof;

FIG. 5 is a bottom plan view thereof;

FIG. 6 is a front elevational view thereof;

FIG. 7 is a top plan view, in enlarged scale, of the forceps jaws of the view shown in FIG. 2;

FIG. 8 is a right side elevational view, in enlarged scale, of the forceps jaws of the view shown in FIG. 1;

FIG. 9 is a top plan view of the jaws of a gallbladder forceps showing a second embodiment of our new design;

FIG. 10 is a top plan view of the jaws of a gallbladder forceps showing a third embodiment of our new design;

FIG. 11 is a top plan view of the jaws of a gallbladder forceps showing a fourth embodiment of our new design, the front, rear and sides of each embodiment being identical; and,

FIG. 12 is a right side elevational view illustrating the overall length of tubular housing.

FIG. 3

FIG. 9

FIG. 10
